CLAIM

The ornamental design for container for preparation of sauce-covered chicken wings, as shown and described.

DESCRIPTION

FIG. 1 is a perspective view of a vessel or container for coating fried chicken wings with sauce, showing a lower bowl and an interfitting upper lid, embodying our new design.

FIG. 2 is a front elevational view thereof, other elevational views being substantially identical.

FIG. 3 is a top plan view thereof.

FIG. 4 is a bottom plan view thereof; and,

FIG. 5 is a cross-sectional view taken along

FIG. 3.
